UNITED STATES PATENT OFFICE.

LEE DE FOREST, OF NEW YORK, N. Y., ASSIGNOR TO WIRELESS TELEGRAPH COMPANY OF AMERICA, A CORPORATION OF NEW JERSEY.

WIRELESS-SIGNALING APPARATUS.

SPECIFICATION forming part of Letters Patent No. 749,131, dated January 5, 1904.

Original application filed March 6, 1901, Serial No. 50,078. Divided and this application filed December 8, 1902. Serial No. 184,312. (No model.)

To all whom it may concern:

Be it known that I, LEE DE FOREST, a citizen of the United States, and a resident of the city of New York, borough of Manhattan, 5 in the county and State of New York, have invented certain new and useful Improvements in Wireless-Signaling Apparatus, of which the following is a specification.

My invention relates to an improvement in wireless-signaling apparatus designed, primarily, to enable a directional or concentrating effect to be given the signaling-waves radiated, whereby their effectiveness may be increased in any given direction and to similarly increase the effectiveness of receiving waves when placed in proper relation to the direction of their travel. My invention is also capable of indicating approximately the direction from which a signal is received.

This application is a division of an application for an improvement in space telegraphy, Serial No. 50,078, filed March 6, 1901.

My invention comprises the novel features and parts and combinations thereof, which will be hereinafter described, and particularly pointed out in the claims.

In the figures of the drawings accompanying herewith I have illustrated an apparatus embodying my invention.

Figure 1 shows my invention embodied in a sending or transmitting apparatus. Fig. 2 shows my invention embodied in a receiving apparatus.

In the accepted theory of the nature of electromagnetic waves in space and conducting bodies when the aerial conductor at the sending-station is charged lines of force radiate from the whole surface of such conductor in all directions and normal to such surface, and if the other side of the spark-gap is earthed or grounded (as is the common practice in apparatus of this nature) the lines of force radiating from the surface of the aerial conductor traverse circular paths from such conductor and at their other ends rest upon or reach the surface of the earth, thus forming, so to speak, semispheres with the aerial conductor as an axis. When the spark passes across the spark-gap, the electrical charge in

the aerial or generating conductor oscillates or surges to and fro throughout the length of such conductor, the waves being reflected at the upper end of the conductor, at which point a static loop is formed. The other or lower ends of these lines of force and which rest in the earth move outwardly from the center over the surface of the earth in ever-widening circles. Consequently an electrical displacement opposite in sign to the electrical displacement at that instant traversing the upright conductor thus travels outwardly with the velocity of light in all directions alike in the form of a circle of ever-increasing diameter with the conductor as an axis, which wave follows the surface of the earth or water, finally reaching distant points or receiving-stations even when located far below the horizon. For a fuller description of the theory of the propagation of the field of force in the Hertzian telegraph I refer to my article on this theme in the *Electrical World and Engineer* of May 17, 1902.

In the practical operation of a wireless-signaling apparatus and in order to secure the greatest amount of efficiency it is desirable to provide means whereby the direction of propagation of the energy waves radiated from the generating aerial conductor at the transmitting-station may be controlled and determined.

Referring to Fig. 1, reference-sign A designates an aerial or radiating conductor. Instead, however, of directly connecting this conductor to ground through the spark-gap of its charging and discharging apparatus, as has been usual heretofore, I lead off from the base of such conductor an insulated horizontal wire or conductor B. In practice I prefer to employ a length of vertical or aerial conductor A corresponding to one-quarter a wave length and a length of horizontal conductor B corresponding to one-half a wave length.

By the arrangement above described wherein a horizontal insulated wire or conductor is employed and led off in a particular direction from the aerial conductor, said horizontal wire or conductor being arranged any

convenient distance above the surface of the earth and which at the end thereof farthest removed from the aerial conductor is grounded either directly or through a spark-gap, as indicated at B', I have found that a condition is produced differing from the usual condition above described—that is, I have found that the lines of force generated in the aerial conductor by the surges occurring therein instead of radiating in all directions from such conductor are concentrated in the plane which contains the two wires or conductors A and B, and thus the plane of these conductors or wires determines the plane or direction of propagation of the energy waves which are radiated.

The charging apparatus may be of the usual or any suitable construction and arrangement. As illustrative of an operative embodiment of charging apparatus I have shown an induction-coil construction, wherein the terminals of the secondary coil F are respectively connected to the primary spark-balls C D.

25 G designates the primary of the induction-coil, in the circuit of which are arranged a generator H and interrupter J, of any suitable or usual character.

The charging apparatus may be connected 30 to the aerial and direction-determining conductors at any desired or convenient point, and while I have shown the primary or charging-spark terminals C D, respectively, connected to the adjacent ends of the conductors A and B, I do not desire to be limited or restricted to this location and arrangement.

In the arrangement shown, however, it will be observed that before the spark occurs between the terminals or balls C D the vertical and horizontal wires or conductors will be charged oppositely, and consequently the lines of force joining these two charges will lie mainly in the plane determined by these wires or conductors, thus giving a direction 40 of propagation to these waves, as well as concentrating such waves in such direction of propagation. When the spark occurs, the electrical surges set up in the two wires or conductors find earth through the secondary spark-gap B'. Consequently the resulting energy wave is in the form of a plane-polarized wave with its direction of propagation lying in the direction of the length of the wire B, and having once acquired a direction of propagation such direction is maintained, except as diffusion affects the same as it progresses outwardly over the surface 50 of the earth or water.

If desired, and in order to still further define and determine the plane of propagation of the energy waves, a second wire (indicated in dotted lines at M) equal in length and parallel with respect to wire B may be led off from the top end of the wire or conductor A. 60 This arrangement also produces a more resonant system.

If desired, and in order to augment or in-

crease the intensity of the radiated energy waves, instead of employing the additional horizontal wire M an additional vertical conductor A' may be employed, as indicated in dotted lines in Fig. 1, which conductor is equal in length and arranged parallel with respect to conductor A and connected at the other end of the horizontal wire B in a manner similar to the connection of such wire to conductor A. In this arrangement it is preferred to have the charging apparatus connected to the apparatus at a point midway the length of conductor B, which in this case 80 should be of a length corresponding to a half-wave length. In such event, however, a ground connection (indicated at E) should be provided for the lower end of the conductor A, which ground connection is reached through 85 a spark-gap similar to the spark-gap B' at the far end of conductor B, as is indicated by the dotted earth connection and spark-ball D'. This spark-gap then becomes a secondary spark-gap and the primary spark-gap is 90 moved to the central position between the conductors A and B. By thus spacing the two aerial conductors A A' a half-wave length apart the waves given off or radiated from conductor A on arriving at a point coinciding 95 with conductor A' serve to reinforce or augment the waves given off or radiated from the latter. By revolving or shifting the position of the horizontal wire B about conductor A as a center it will be readily seen that the lines 100 of direction of propagation of the radiated energy waves may be controlled.

If desired, and in order to increase the current represented by the electrical surges in the conductors A and B, I may introduce in 105 said conductors and at a point adjacent to the nodes therein suitable condensers, as indicated at L, thereby effecting a radiation of a larger amount of energy, and in order to secure the advantage of a longer duration of 110 the electrical surges in order to send out longer wave-trains with the same amount of energy I may also introduce in the conductors A and B at points adjacent to the nodes therein 115 momentum-coils, as indicated at K.

By the construction and arrangement of transmitting apparatus above described I am enabled to efficiently determine the direction and plane of propagation of the energy-waves sent out. I am also enabled to control and 120 govern such direction of propagation, so as to direct the same toward any particular distant receiving-station. I also secure the advantage of a concentration of the radiated energy waves, thus increasing the range of 125 the apparatus or the distance through which signals may be transmitted through space, and I also secure the advantages of longer duration of electrical surges and an increased amount of the energy which produces 130 such electrical surges.

In order to operate an apparatus of the nature to which the present invention relates to the best advantage, the coherer or other

wave-responsive device at the receiving-station should be so placed and located that a maximum of positive potential and a maximum of negative potential shall occur at the two terminals thereof simultaneously. This result is not accomplished in the arrangement of the apparatus wherein a single aerial receiving-conductor is used connected to earth through a coherer or other form of wave-responsive device, for in such a case one terminal of the coherer or wave-responsive device being connected to earth is at zero-potential.

In carrying out my invention I propose to employ two or a coöperating pair of aerial receiving or collecting conductors, in each of which stationary waves are produced by the cutting thereby of the lines of force or waves of energy radiated from the transmitting-station, as above explained, and I propose to so separate and place the collecting-conductors and the coherer or other wave-responsive device so that the latter will be located at a point where occurs a loop of positive potential in the stationary waves of one receiving wire or conductor and a loop of negative potential in the stationary waves of the other receiving wire or conductor, thus securing conditions of maximum efficiency in the receiving device. Different arrangement for accomplishing this result may be employed. One arrangement is shown in Fig. 2, wherein reference-sign A^2 designates one of the aerial receiving or collecting conductors and A^3 the other. These conductors should each be preferably one-quarter-wave length in length and are spaced apart a distance of one-half-wave length. B^2 designates the coherer or other wave-responsive device employed.

Any form of wave-responsive device may be used. I have shown a form of receiving or wave-responsive device of the anticoherer type, which I have employed, wherein contact-points B^3 B^4 are employed and arranged in series in a wire or conductor connecting the aerial receiving-conductors A^2 A^3 , a porous or other body B^5 being interposed in series between the adjacent or proximate ends of contacts B^3 B^4 in order to support or maintain a fluid or other substance in the space between said contacts.

A^4 designates the indicating device, herein shown as a telephone-receiver, but which may be of any suitable form.

A^5 is a local battery, and A^6 suitable choke-coils. The choke-coils, the signal-indicating instrument A^4 , the battery A^5 , and the wave-responsive device, herein shown as consisting of the contacts B^3 B^4 , are all arranged in series in the local-battery circuit, the wave-responsive device being also located in series with the aerial receiving-conductors A^2 A^3 .

Now by the arrangement above described and by respectively connecting the conductors A^2 A^3 at the lower ends thereof to earth at B^6 B^7 it will be seen that the electrostatic waves generated or produced in the two ver-

tical receiving-conductors by the signal-transmitting-wave trains will have nodes at the points a b and lines a' a'' , being graphic representations, respectively, of the positive and negative stationary waves having the point a as their node and reference-signs b' b'' representing, similarly and respectively, negative and positive waves having the point b as their node. The location of the wave-responsive device B^2 at a point midway between the points a b will bring the terminals of such resistance device at points where occurs a loop of positive potential on one side and a loop of negative potential on the other side, and hence at a point where the maximum effect is secured and the greatest possible advantage derived.

By the usual practice, as previously pointed out, one terminal of the wave-responsive device being directly connected with the earth is at zero potential, and the difference of potential between its terminals can thus be only half what it would be by my plan. This increased effect is produced in its maximum degree only when the plane which contains the aerial receiving-conductors A^2 A^3 coincides with the plane of propagation of the energy waves radiated from the transmitting-station, as otherwise the stationary waves when they reach the wave-responsive device would not be opposite in phase. Any deviation of the plane of the receiving-conductors A^2 A^3 from coinciding relation with respect to the direction of travel of the energy waves radiated will result in a decreased efficiency at the receiving-station and will be noticeable. The arrangement above described, wherein the receiving-conductors are a quarter-wave length in length and are spaced one-half-wave length apart, affords means for detecting the direction from which proceeds the arriving energy waves, and by shifting the plane of the receiving-conductors A^2 A^3 about a vertical axis the direction from which proceeds the arriving energy waves may be determined. This is a point of obvious importance in apparatus of this kind, and especially when employed for signaling at sea or on board ship. The shifting of the plane which contains and is determined by the two aerial receiving-conductors may be effected in any suitable or convenient manner.

Having thus described my invention, what I claim, and desire to secure by Letters Patent, is—

1. In wireless signaling the combination with a vertical and a horizontal linear conductor connected in series with the earth, of a wave-producing device connected to synchronously produce electrical waves in both of said conductors.

2. In a wireless signaling apparatus in combination, a radiating-antenna, a horizontal conductor of relatively small transverse dimensions connected in series with the antenna and the earth and coöperating with said antenna to give a concentrating or directional effect to the waves radiated, and means

- for producing synchronous oscillations in both of said conductors.
3. In wireless signaling, the combination with a vertical radiating-conductor and a horizontal linear conductor placed in series between the vertical conductor and the earth and extending from the vertical conductor in the direction the signal is to be sent, and means for producing electrical waves in the aerial circuit thereby formed.
4. In wireless signaling, the combination with a vertical radiating-conductor equivalent in length to one-quarter of a wave length, a horizontal conductor equivalent in length to a multiple of a quarter of a wave length, said conductors being connected in series with the earth and means for synchronously setting up electrical oscillations in both said radiating-conductors.
5. The means for giving a direction or concentrating effect to the radiations from a vertical conductor, comprising a horizontal conductor extending from said vertical conductor in the direction of the concentration desired, and adapted to participate with said vertical conductor in the electrical oscillations set up therein and a ground connection for the end of said horizontal conductor a multiple of a quarter-wave length from the vertical conductor.
6. In wireless signaling, the combination with a vertical and a horizontal linear conductor of a wave-producing device, including a spark-gap having one ball connected with proximate ends of each of said conductors.
7. In wireless signaling, the combination with a vertical and a horizontal linear conductor, a wave-producing device connected with both of said conductors, and a common earth connection for both of said conductors including therein a spark-gap.
8. In wireless signaling, the combination with a vertical radiating-conductor, and a horizontal conductor of means for producing oscillations in both conductors connected thereto at the base of the vertical conductor, and a common ground connection for both located a half-wave length from the vertical conductor.
9. In wireless signaling, the combination with a vertical radiating-conductor and a horizontal conductor of means for producing oscillations in said conductors connected thereto at the base of the vertical conductor, and a common ground connection for both conductors connected with the horizontal conductor a half-wave length from the vertical conductor and containing a spark-gap.
10. In wireless signaling the combination with a horizontal conductor, two spark-gaps having one member of each connected respectively with opposite ends of said conductor, a vertical radiating-conductor connected with the other member of one spark-gap, and an earth connection with the other member of the other spark-gap.
11. In wireless signaling apparatus, the combination with two conductors angularly disposed with relation to each other and having adjacent ends, of a wave-producing mechanism connected with said conductors at the apex of the angle thereof between, and a ground connection for one of the conductors a multiple of quarter-wave length from said angle.
12. In a wireless signaling apparatus, the combination with two transmitting-conductors angularly disposed relative to each other and having adjacent ends, one of said conductors being equivalent in length to a quarter-wave length and the other equivalent in length to a half-wave length of a wave-producing mechanism connected with both conductors at the apex of the angle therebetween, and a ground connection to the longer conductor at its opposite end.
13. In a wireless signaling system, the combination with signal-wave producing and radiating device, of a receiving device comprising two wave-collecting conductors located a half-wave length apart in the direction of travel of the received waves, and each provided with a ground connection, a conductor connecting said collecting-conductors and a wave-responsive device interposed midway in said connecting-conductor.
14. In a wireless signaling system the combination with a signal-wave producing and radiating mechanism, of a receiving device comprising two collecting-antennæ separated a half-wave length, each provided with a ground connection and being adapted to be swung about a vertical axis, a conductor connecting their base and a signal-indicating apparatus in said connecting-conductor midway its length.
15. In an apparatus of the class described, a horizontal conductor having spark-gaps at the ends thereof, the spark-gap at one end of said conductor being connected to earth, an aerial conductor connected to one of the terminals of the spark-gap at the other end of said horizontal conductor, and a generator of electric potential having its terminals respectively connected to the terminals of the said spark-gap.
16. In an apparatus of the class described, an aerial conductor and a coöperating horizontal conductor, in combination with a spark-producing apparatus connected to said conductors at a node or neutral point of the waves therein, and condensers arranged in said conductors adjacent to such node or neutral point.
17. In an apparatus of the class described, an aerial conductor and a coöperating horizontal conductor, in combination with a spark-producing apparatus having the terminals thereof respectively connected to adjacent ends of said conductor, in combination with momentum-coils introduced into said conductors adjacent such terminal connections.
18. In an apparatus of the class described, an aerial conductor and a coöperating hori-

zontal conductor and a spark-gap interposed between them, in combination with a generator of electric potential having the terminals thereof respectively connected to the 5 said spark-balls, and momentum-coils and condensers arranged in said conductors adjacent to said spark-gap.

19. In an apparatus of the class described, a radiating-conductor in combination with a 10 coöperating conductor arranged in rectangular relation with respect thereto, and means connected at the apex of the angle between said conductors adapted to produce electrical surging of opposite signs in said respective 15 conductors.

20. In an apparatus of the class described, and in combination with means for determining the plane of propagation of energy

waves, a receiving apparatus including two 20 wave-collecting aerial conductors each provided with earth connections and spaced a half-wave length apart, a horizontal conductor connecting said aerial conductors and a receiving instrument so located in the horizontal conductor that a maximum of positive 25 potential and a maximum of negative potential simultaneously occurs at the respective terminals thereof.

In testimony whereof I have hereunto affixed my signature, this 4th day of December, 1902, in the presence of two witnesses.

LEE DE FOREST.
